UNITED STATES PATENT OFFICE.

SAMUEL F. ALLEN, OF CHICAGO, ILLINOIS.

IMPROVEMENT IN FEED-WATER HEATERS FOR LOCOMOTIVES.

Specification forming part of Letters Patent No. 41,591, dated February 13, 1864.

To all whom it may concern:

Be it known that I, SAMUEL F. ALLEN, of Chicago, in the State of Illinois, have invented certain new and useful Improvements in Feed-Water Heaters for Locomotives; and I hereby declare that the following is a true and exact description of the same, reference being had to the accompanying drawings, and to the letters of reference marked thereon.

The nature of my invention consists in the use of certain devices by which the boilers of locomotives can be supplied with hot water, thereby facilitating the production of steam.

Figure 1 in the annexed drawings represents a side elevation of the boiler, with sectional view of the flues, and also an end view of the heater. Fig. 2 is a longitudinal section of the heater Q, with compound pipes R and exhaust-pipes T attached. Fig. 3 is a side view of exhaust-pipe, with the opening through which the deflecting tongue projects.

A in Fig. 1 represents the boiler, and Q the heater placed beneath A and at right angles to it. The heater Q is securely fastened to the sides of frame F by means of the lugged heads E E. By this arrangement the heater is made to answer as a brace, and thus give stability to the frame F. The lugged heads E are held together by longitudinal bolts P, which can be easily removed when it becomes necessary to repair or cleanse the heater Q.

R represents the compound pipes, which connect the heater Q with the exhaust-pipes T. The office of pipes R is to convey a sufficiency of steam into heater Q to raise the water in Q to the desired temperature. The pipes T are fastened together by means of the yoke and

set-screws X, so that one pipe can be removed without deranging the other.

A² represents a valve for regulating the exhaust steam which enters Q through the compound pipes R. The pipes R and T are so constructed and arranged that the pressure of steam in heater Q will be equal to that in pipes T. This result is chiefly attained by the use of the deflecting tubular tongue C, which admits as much steam into pipes R as is necessary to preserve the equilibrium above stated, and discharges the remainder through pipes T.

B² represents the plunger, which is designed to prevent any hard substance that may enter through pipes T from striking against and injuring the flues I, Fig. 2. To effect this object the end of the plunger B² is closed and the sides open for the escape of the steam.

H in Fig. 1 represents the pipe through which the cold water is forced into the heater Q, and L the pipe through which hot water enters the boiler A; and S represents the escape-pipe.

Having thus described my invention, what I claim, and desire to secure by Letters Patent, is—

The combination of the compound pipes R, the exhaust-pipes T, the regulating-valve A², the deflecting-tongues C, the yokes X, and the heater Q, substantially as herein set forth.

In testimony that I claim the foregoing I hereby affix my signature in the presence of two witnesses.

SAMUEL F. ALLEN.
